UNITED STATES PATENT OFFICE.

HENRY M. SHERWOOD, OF CHICAGO, ILLINOIS.

DESIGN FOR FRAMES FOR CHURCH, HALL, AND LAWN-SEATS.

Specification forming part of Design No. 5,282, dated September 26, 1871.

To all whom it may concern:

Be it known that I, HENRY M. SHERWOOD, of Chicago, in the county of Cook and State of Illinois, have invented a Design for the Frame of a Church, Hall, School, and Lawn-Seat, of which the following is a specification:

The nature of my design is fully represented in the accompanying photographic illustration, to which reference is made.

Figure 1 represents an iron casting which is made to sustain the end of the seat. Fig. 2 represents an iron casting used for sustaining the center of the seat.

Fig. 1 is made of a single piece of cast-iron, with legs A and B connected by curved arm X, which sustains the seat, and terminating in a single standard, C, to which the back of the seat is attached, and is strengthened by braces D and E. To give it more beauty and strength is arm F, which, with circle G, connects standard C to leg B. Fig. 2 is made of a single piece of cast-iron, with legs H I connected by curved arm Z, which sustains the seat, and terminating in a single standard, K, to which is attached the back of the seat. This frame is strengthened by braces L M. That part of the frame in Fig. 1 inclosed by the arm F, standard C, arm X, and circle G being

two curved leaves, N and O, and bud Q. These, with the quarterfoil P lying between leg A, brace D, and arm X, together with quarterfoil R, leaves J S and bud Y inclosed by braces E and D, and leg B carved in basso-relievo, so as to give the design a neat and beautiful appearance. In Fig. 2, inclosed by legs H and I, arm Z, and brace M, are quarterfoils T V and leaf W, carved in basso-relievo, so as to give strength and beauty to the frame.

I am aware that cast-iron frames for church, hall, school, and lawn seats are not new, and I do not claim them. The distinctive character of my design is found in the basso-relievo ornaments, composed of leaves, quarterfoils, and buds.

What I claim as my invention is—

A design for church, hall, school, and lawn-seat frames, with ornaments of leaves, quarterfoils, and buds, substantially in the manner above described.

In testimony whereof I have signed my name to this specification in the presence of two subscribing witnesses.

HENRY M. SHERWOOD.
